US00D621860S

(12) **United States Design Patent**
Fukano et al.

(10) **Patent No.:** US D621,860 S
(45) **Date of Patent:** ** Aug. 17, 2010

(54) **ELECTRIC ACTUATOR**

(75) Inventors: **Yoshihiro Fukano**, Tsukubamirai (JP);
Toru Sugiyama, Tsukubamirai (JP);
Masaki Miyahara, Tsukubamirai (JP)

(73) Assignee: **SMC Corporation**, Chiyoda-ku, Tokyo (JP)

(**) Term: **14 Years**

(21) Appl. No.: **29/312,305**

(22) Filed: **Oct. 14, 2008**

(30) **Foreign Application Priority Data**

Apr. 18, 2008 (JP) 2008-009998

(51) **LOC (9) Cl.** **15-09**

(57) **CLAIM**

The ornamental design for an electric actuator, as shown and described.

DESCRIPTION

FIG. 1 shows a front view of an electric actuator showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof; and,

FIG. 7 shows a top, front and left side perspective view thereof.

1 Claim, 4 Drawing Sheets
